(57) **CLAIM**

We claim the ornamental design for a bottle, substantially as shown and described.

DESCRIPTION

FIG. 1 is a top, front, left side perspective view of a bottle, showing our new design;

FIG. 2 is a front elevational view thereof, the rear elevational view being a mirror image;

FIG. 3 is a right side elevational view thereof;

FIG. 4 is a top plan view thereof; and,

FIG. 5 is a bottom plan view thereof.

The broken lines shown in the drawings are for illustrative purposes only and form no part of the claimed design.
